LAWN SPRINKLER

Stephen D. Baker, Eau Gallie, Fla.

Application June 16, 1937, Serial No. 148,425

1 Claim. (Cl. 299—114)

My invention relates to lawn sprinklers which are designed to cause a spiral movement of the water and to discharge it in a fine spray over a circular area.

Among the objects of the invention is the production of a sprinkler of simple construction which is efficient and comparatively inexpensive to manufacture and has no moving parts, one which is preferably made of porcelain and, therefore, not subject to rust or corrosion, and which is self-cleaning in that it is capable of ejecting the ordinary sand or dirt which it is apt to encounter in use, and thus prevent clogging.

These objects I attain in the novel combination and arrangement of parts herein described and claimed, the nature and use of which will be obvious from their illustrations in the accompanying drawing, in which:—

Figure 1 is a perspective view of my improved lawn sprinkler;

Figure 2 is a plan view of the same;

Figure 3 is a section on the line 3—3 of Figure 2;

Figure 4 is a bottom view of the casing of my device;

Figure 5 is a plan view of the plug member of the same;

Figure 6 is an end view of the casing; and

Figure 7 is a perspective view of said plug member.

In the drawing in which similar reference numerals denote corresponding parts, 1 designates a casing, the interior of which is formed into a circular chamber 2 by means of wall 3. The circular wall 3 terminates a short distance from the bottom of the casing to provide a flange or seat 4, and is pierced by a port 5, which communicates with a screw-threaded inlet opening 6 in the outer wall of the casing for connection to a water supply hose or pipe. The opening 6 extends through the casing to the wall 3 which is closed to said opening except through the tangential port 5 cut into the wall 3 which is much smaller than the opening 6. On the flange 4 and substantially opposite the port 5 is a projection 7. In the top of the casing is an outlet orifice 8.

Adapted to fit into the chamber 2 of the casing is a plug member 9 which consists of a base 10, a cylindrical post 11, slightly tapered at 12 and rising from base 10 and partly encircling the post 11 is an inclined plane 13. The said base, post and inclined plane are in one piece and the slightly tapered top of the post is made smaller than the diameter of the outlet orifice 8. In the base is a recess or cut-out part 14. The hole 15

is for the purpose of holding the sprinkler in place by means of a nail or otherwise.

In the manufacture of the device, the members 1 and 9 are separately constructed and then combined. As will be obvious, this is done by inserting member 9 into chamber 2 of casing 1 so that projection 7 on the flange fits into recess 14 on the base 10. The tapered top 12 of the post 11 will then project slightly within the outlet orifice 8. The seat or flange 4 is located at such a distance from the bottom wall of the casing that when member 9 is in proper position its base will be flush with the bottom of the casing and it will be spaced from the wall of chamber 2 except where its inclined plane substantially contacts the wall of said chamber.

In manufacturing the device the two parts are formed of pulverized clay by means of dies. They are then cemented together with a solution of clay and water and after being thoroughly dried are dipped into, or sprayed with, china glaze and placed in a kiln and fired.

In the operation of the device the water entering the inlet port 5, which is at a tangent to the normal flow of the water, is given a rotary motion by contacting the inner circular wall of the chamber 2 and the post 11. This swirling is continued and intensified as the water is ascending inclined plane 13 and directed toward the orifice 8. As the water approaches the orifice, its velocity is increased due to the restriction of the orifice by the top of the post, and it emerges in a fine circular spray.

It will be seen from the foregoing that with a minimum of fixed parts I have devised a sprinkler of the utmost simplicity.

What I claim is:—

A lawn sprinkler comprising a casing the top of which is substantially flat and is pierced with an outlet orifice, the interior of the casing constituting a circular chamber, a screw-threaded opening in a side wall of the casing for connection to a source of supply, a tangential port in said wall connecting said opening with the circular chamber adjacent the bottom thereof, a cylindrical taper-topped post provided with an inclined plane which partly encircles it positioned in said chamber with the lower end of said plane terminating adjacent said port, the tapered top of the said post extending slightly into the said outlet orifice, whereby entering liquid is caused to move in an ascending spiral flow to said outlet orifice substantially as and for the purpose set forth.
